UNITED STATES PATENT OFFICE.

HUGH T. LIPSCOMB, OF BALTIMORE, MARYLAND.

ROTARY TOOTH-BRUSH.

1,050,282.

Specification of Letters Patent. Patented Jan. 14, 1913.

Application filed September 13, 1912. Serial No. 720,289.

To all whom it may concern:

Be it known that I, HUGH T. LIPSCOMB, a citizen of the United States, residing at Baltimore, in the State of Maryland, have 5 invented a new and useful Rotary Tooth-Brush, of which the following is a specification.

The present invention relates to improvements in rotary tooth brushes, the primary 10 object of the invention being the provision of a novel mechanism for releasing a spring motor for rotating the brush in one direction, the casing containing the spring motor and releasing mechanism constituting the 15 handle for manipulating the brush.

With the foregoing and other objects in view which will appear as the description proceeds, the invention resides in the combination and arrangement of parts and in 20 the details of construction hereinafter described and claimed, it being understood that changes in the precise embodiment of the invention herein disclosed can be made within the scope of what is claimed without 25 departing from the spirit of the invention.

In the drawings Figure 1 is a longitudinal sectional view through the casing or handle with the parts in locked position. Fig. 2 is a section taken on line 2--2 of Fig. 1. 30 Fig. 3 is a section taken on line 3--3 of Fig. 1.

Referring to the drawings, the numeral 1 designates the casing which constitutes a handle, the same being composed of two 35 members divided longitudinally and held together by means of the bolts 1'.

Journaled in one wall of the casing is a shaft or stud 2 having upon the outer end thereof a winding disk 3 to which is connected one end 4 of the spring 5, whose other end is connected to the casing 1, said spring constituting a motor for operating the brush B as will presently appear. Keyed upon the inner end of the shaft 2 is a disk 7 45 carrying a pawl or detent 8 disposed in co-active relation with the teeth of the collar 9, carried by the large disk 10 provided with the bevel gear teeth 11. The disk 10 and spring 5 constitute the motor, the ratchet 50 connection at 8 providing a means whereby the handle 3 may be rotated in one direction without affecting the disk 10 and during the winding of the spring, the movement in the opposite direction being imparted by the 55 spring 5 unwinding to rotate the disk 10.

The gear 11 of the disk 10 is in mesh at all times with a small bevel pinion 12 keyed upon the inner end of the brush carrying shaft 13, said shaft 13 being properly journaled within the casing 1 and carrying 60 thereupon the toothed wheel 14 whose spinning is regulated by means of the escapement detent 15 journaled upon and carried by the post 16.

In order to release the toothed disk 14 to 65 permit the brush B to be rotated, the lever 17 provided with the disk engaging point 18, is pivoted at 19, while the opposite end is controlled by the push pin 20 readily accessible to the operator exteriorly of the casing 1. The spring 21 is so disposed as to normally hold the point 18 in engagement with the toothed disk 14 so that the shaft 13 is locked against rotation. 70

From the foregoing description, taken in 75 connection with the drawings, it is evident that after the spring motor is wound, and in order to manipulate the brush B, that the operator will grip the casing 1 so that the thumb is presented to the push pin 20, and 80 pushes the pin 20 so as to release the point 18 of the lever 17 and the ratchet 14, which due to the escapement detent 15 will regulate the rotation of the shaft 13 which is 85 freed to the action of the motor. The continual manipulation of the pin 20 will produce the desired rotation of the brush and after the spring motor has expended its power, the spring is wound by the manual 90 rotation of the shaft 2 through the disk 3. 90

What is claimed is:

1. A rotary tooth brush, comprising a casing, an arbor journaled in the casing, a spring operably connected to the casing and arbor, a disk keyed upon the inner end of the arbor, a detent carried thereby, a toothed disk rotatably mounted upon the arbor and provided with ratchet teeth to coact with the detent of the arbor disk to operably connect the geared disk to the arbor, a brush carrying shaft operably connected to the geared disk, an escapement device for regulating the speed of rotation of the shaft, and manually controlled means for locking and releasing the shaft. 95 100

2. A rotary tooth brush, comprising a casing, an arbor journaled in the casing, a spring operably connected to the casing and arbor, a disk keyed upon the inner end of the arbor, a detent carried thereby, a 105 110

toothed disk rotatably mounted upon the arbor and provided with ratchet teeth to co-act with the detent of the arbor disk to operably connect the geared disk to the arbor, a brush carrying shaft operably connected to the geared disk, a toothed wheel fast to the shaft, an escapement operably connected to the toothed wheel, a spring actuated locking lever disposed to engage 5 the toothed wheel to lock the shaft against 10

rotation, and a manually controlled means for releasing the lever.

In testimony that I claim the foregoing as my own, I have hereto affixed my signature in the presence of two witnesses.

HUGH T. LIPSCOMB.
